L. PIERCE

ROLLING MILL

Filed March 18, 1926

Patented June 21, 1927.

1,633,349

UNITED STATES PATENT OFFICE.

LEON PIERCE, OF NEW YORK N. Y.

ROLLING MILL.

Application filed March 18, 1926. Serial No. 95,570.

The main object of this invention is to provide a rolling mill which is inexpensive in cost, simple in design, and is provided with an idler roll and two driven supporting rolls which are adapted to form an internal bead or depression upon a length of piping which serves as a coupling between a pair of pipe lengths used in foundation work.

Another object is to provide a rolling mill having an idler forming roll which presses the material being flanged into contact with complementary rolls through the aid of compressed air cylinders and pistons, which latter engage the bearing blocks of the idler roll and lower the same.

Still another object is to provide a rolling mill having an idler forming roll which presses internal flanges upon sleeves intermediate their length and means for lifting the idler roll and removing one of the bearing blocks so that the sleeve may be mounted conveniently upon the idler roll without dismantling any additional parts of the rolling mill.

The above and other objects will become apparent in the description below, in which characters of reference refer to like-named parts in the drawing.

Referring briefly to the drawing, Figure 1 is a front elevational view of the rolling mill.

Figure 2 is a side elevational view of the same.

Figure 3 is a sectional plan view taken on line 3—3 of Figure 1.

Figure 4 is a sectional elevational view of the rolling mill, showing the idler roll in raised position preparatory to removing a finished sleeve therefrom.

Referring in detail to the drawing, the numeral 10 indicates upright plates which are arranged at the corners of the rolling mill. Intermediate the height of these upright plates, a platform is formed by suspending two I-beams 11 and 12 from supporting beams 13 and 14 which extend toward each other from the plates 10 and are riveted to said plates. This platform extends across the width of the rolling mill and supports a pair of compressed air cylinders 15 and 16. The cylinders are seated on the I-beams 11 and 12 and are clamped between these I-beams and connecting I-beams 17 and 18 which are mounted and securely attached to the upper ends of the uprights 10. Between the lower ends of the

uprights 10, plates 19 and 20 are fixed. These plates form part of the frame of the rolling mill and have vertical channels 21 formed therein. The channels receive bearing blocks 22 and 23 which receive the opposite ends of a shaft 24 on which an idler roll 25 having a semi-circular groove 26 extending peripherally thereon, is mounted. Below these channels 21, a pair of aligned shafts 27 and 28 are rotatably journaled in the plates 20 and 19 on each side frame. Said shafts have relatively smaller driven forming rolls 29 and 30 mounted thereon which cooperate with the idler forming roll 25 and are provided with semi-circular peripheral ridges 31 which are complementary to the groove 26 in the idler roll and register in said groove portion. These idler rolls are off-set from the center of the rolling mill 75 on both sides of the channels 21. The shaft 28 has a relatively large spur gear 32 fixed to one end thereof on one side of the frame and the remaining shaft 27 has a similar spur gear 33 fixed thereto on the opposite side of the rolling mill. Below the channels 21 and shafts 27 and 28, a drive shaft 34 is journaled in the plates 19 and 20 of the side frames and at one position has a pinion 35 thereon which meshes with the spur gear 33 and at its end has an additional pinion 36 of similar dimensions which meshes with the spur gear 32.

The use of the rolling mill is to form bead-ed sections intermediate the length of a piece of piping to provide internal flanges for forming a coupling, such as illustrated by Patent No. 1,507,138. In inserting the length of pipe in place preparatory to bead-ing the same internally, the bearing blocks 22 and 23 are lifted by tackle suspended from above the rolling mill and the block 22 is removed from the end of the shaft 24 and the coupling or length of pipe is then slipped over the idler forming roll 25. The bearing blocks are then again lowered after slipping the block 22 over the end of the shaft 24 into the channels 21. Air then enters the cylinder 16 through inlet pipes not shown on the drawing and the piston 37 is lowered, urging the blocks downward so that the pipe being formed into a coupling lies in tight contact with and rides on the surface of the bead 31 on the forming rolls 29. The forming rolls 29 and 30 rotate in the same general direction and are driven from a single shaft 34 which would not be possible

were any other driving means substituted, it being understood that a large ratio between gears is necessary in order to reduce the rotation of the forming rolls 29 and 30 with respect to the rotation of the driven shaft 34. To permit both rolls to be driven in unison, a single gear is attached to each shaft 28 and 27 on opposite sides of the frame and these spur gears 32 and 33 are 10 driven by individual pinions placed on opposite sides of the frame and mounted at these positions rigidly on the drive shaft.

It is to be noted that certain changes in construction may be made without departing from the spirit and scope of the invention.

In mounting a sleeve upon the idler roll of the mill, it is necessary that the bearing block 22 be made removable so that the end 20 of the idler roll is exposed when raised to the position shown in Figure 4. To accomplish raising of the idler roll, block and fall tackle is necessary. One block and fall is used to raise one of the bearing blocks while the 25 bearing block 22 is raised with another block and fall to a position where it is out of the way so that a sleeve may be conveniently slipped over the idler roll.

I claim:

30 1. In a rolling mill, a pair of end frames, an idler roll having a groove, driven rolls having ridges thereon cooperating with the grooves on the idler roll, compressed air cylinders mounted on said frames above said

rolls, bearing blocks supporting said idler 35 roll, one of said bearing blocks being guided vertically the entire height of one of said frames, the opposite bearing block of said idler roll being guided vertically to a position intermediate the height of the opposite 40 frame, and means for driving said driven rolls from opposite ends by the same transmission shaft.

2. In a rolling mill, a pair of end frames, 45 an idler roll having a groove, driven rolls having ridges thereon cooperating with the grooves on the idler roll, compressed air cylinders mounted on said frames above said rolls, bearing blocks supporting said idler roll, one of said bearing blocks being guided vertically the entire height of one of said frames, the opposite bearing block of said 50 idler roll being guided vertically to a position intermediate the height of the opposite frame, the guide means for said bearing blocks comprising a pair of plates spaced apart and rigid with each other on one frame member, said plates extending the height of said frame member guiding one of 55 said bearing blocks vertically the entire height of the frame, a similar pair of plates on the opposite frame member ending intermediate the height of said frame permitting the opposite bearing block to be removed 60 from said guide means when removing said idler roll.

In testimony whereof I affix my signature.
LEON PIERCE.
